UNITED STATES PATENT OFFICE.

WILLIAM S. WOOTTON, OF SCOTTSBURG, ASSIGNOR TO J. M. CARRINGTON,
OF SOUTH BOSTON, VIRGINIA.

ROAD-ENGINE

SPECIFICATION forming part of Letters Patent No. 375,307, dated December 20, 1887.

Application filed April 15, 1887. Serial No. 234,970. (No model.)

To all whom it may concern:

Be it known that I, WILLIAM S. WOOTTON, of Scottsburg, in Halifax county, in the State of Virginia, have invented new and useful Improvements in Road-Engines; and I do hereby declare that the following is a full and accurate description of the same.

Heretofore all road-engines made may be divided into two classes—first, those with supporting-wheels having hubs and axles running on the ground, and, second, those which lay a temporary track whereon the bearing-wheels may run. To this second division I assign those road-engines which employ centerless wheels or rims next the ground and bearing-wheels which rim on the inner peripheries of said wheels. My invention relates to this latter subdivision.

The advantage gained by the use of centerless track-wheels is in the large diameter with absence of hub and spokes, so that the large diameter of the wheel is not, as with other wheels, an element of weakness; but heretofore, I believe, all road-engines, whether with centerless wheels or not, have been built with all the rigidity attainable; but I have built my engine with all the flexibility attainable, so that the passage of the machine over the undulations of surface on ordinary roads shall have the smallest possible effect to strain the parts of the machine. Everything can then be reduced in weight without diminishing strength.

Referring to the accompanying drawings, Figure 1 is a side elevation of my road-engine. Fig. 2 is a plan of the same. Fig. 3 is a front elevation of the front truck. Fig. 4 is a longitudinal section of the same. Fig. 5 is a horizontal section of the driving-gear. Figs. 6, 7, 8 are details. Fig. 9 is a modification showing a double crank-shaft with one engine. Fig. 10 is a generic form of flexible shaft-connection.

A is the main frame, consisting of a rectangular structure of suitable material properly joined and braced. For the purposes of a road-engine for the transportation of goods from place to place this frame may be from twenty to thirty feet in length, supported at one end upon the driving-wheels and at the

other end upon truck-wheels whose direction may be changed in order to steer the machine as it advances. The frame A is suitably trussed, being provided with tension-rods *b b'* for that purpose. I prefer to locate the motive engine 55 C at the rear end with its fuel-box and tank for water, and reserve the forward end of the vehicle for the reception of the matter to be transported.

D is one of the centerless track rims or 60 wheels. It rests upon the ground and constitutes, as it rolls along, the track for the rear bearing-wheel, E, mounted upon an axle, F, which extends across the machine.

The rim orwheel D, I propose to make about 65 nine (9) feet in diameter. It is constructed with an outer tire, *g*, and an inner cog rim or rack, *h*, and to reduce weight and promote elasticity I propose to place between the tire and the cog-rim a filling of wood, *i*. The cog-rack 70 *h* is provided with a laterally-extended flange, *j*, one on each side, to be traversed by steady rollers *K K'*, which maintain the rim D in position. A pinion, L, has its shaft *d* mounted in boxes *e* on the plate M, and is supported by 75 attachment to the tension truss-rods *b b'*, which pass from the front of the frame A to the rear of the same and beneath the truss-bar *c'*. The plate M is made in two parts, with a longitudinal joint and a central space for the rim or 80 wheel D, said parts being rigidly bolted together, inclosing said rim. The plate M is provided with two boxes, *k k*, to receive short shafts *l l*, which have at their ends the steady-rollers *K'*, which hold and traverse the rim- 85 flanges *j*.

The tension-rods *b b'* support the box-plate M with an elastic support, but with sufficient rigidity to maintain the parts in proper engagement during all the varying strains of action. 90

It will be observed that the wheel or rim D derives its entire support from the box-plate M, and not from several points of attachment to the frame, and therefore there is no possibility of interference or cramping by reason of unequal movements or elastic springing or torsion of the main frame. 95

The box-plate M is located below the horizontal plane of the axis of the wheel D, in or 100

der to reduce the distance from the point of engagement with the pinion L and the point of bearing upon the ground, because the propulsive force is transmitted from said pinion 5 through said rim to the ground in the form of thrust, and the wheel-rim, which constitutes the thrust-bar, being curved, requires more stiffness than though it were straight, and therefore it becomes of importance to decrease 10 its length. At the same time it is advantageous to apply the propulsive force as a vertical lift upon the rim of the wheel, and this would be most effectively accomplished by placing the pinion L in the horizontal plane of the axis of the wheel D; but this would increase the 15 length of the curved thrust-bar to an arc of ninety degrees. I reduce this arc to about forty-five degrees without greatly reducing the horizontal distance of the pinion from the 20 axis of the wheel D, but with a very material reduction in the length of the thrusting-arc of said wheel. These are the reasons for locating the driving-pinion L at the point shown.

A pinion of ordinary construction may be 25 used for a driving-pinion; but the pinion L shown herein belongs to that class known as "lantern-wheels," wherein the teeth or cogs are constituted by round rods secured at their ends in disks fastened to the shaft, thereby 30 leaving a clear open space or cage in the interior, into and through which mud or other obstructing matter may be forced, and thus avoid clogging the wheel. A loose sleeve is placed on each rod-tooth of the pinion to act 35 as a friction-roller, and thus reduce frictional resistance as the pinion and rack roll together.

The box-plate M is provided with one or more sockets to receive and securely hold the ends of the arms N N', which extend therefrom, separated by an angle of about fifty degrees, and carry at their extremities sockets for the spindles of the steady-rollers K K. The arms N N' are each made of two pieces of wood of proper length, securely bolted together in the sockets of box-plate M at one end, and at the other end they are bolted in sockets of the plate P. This structure gives great lateral stiffness to the arm, while it permits sufficient elasticity in the direction of the plane of the wheel to make it easy in its action with the wheel. Being supported entirely by the arms N N', which are both attached to the plate M, and through that receive their only attachment to the frame, the 50 wheel D is practically independent of the frame and its oscillations as it moves over the undulations of the road. At the extremity of the arm N, on each side, there is a longitudinal socket-bearing, m, to receive a spindle of one 55 of the steady-rollers K, which thereby have liberty to approach or recede from the center of the wheel, said spindles slipping endwise in the sockets m.

The propelling-power is derived from a 60 steam-generator, Q, which supplies steam to one or two small engines, C, which are con-

nected with the crank-shaft S in the usual way. The crank-shaft may be driven with one engine, if desired, one being sufficient for mere propulsion; but in turning, the machine will 70 be far more manageable if one of the wheels D can be at rest while the other drives forward. The machine will then pivot on the stationary wheel. To accomplish this with one engine the crank-shaft thereof must be connected with the two pinion-shafts d d by 75 means of separate gearing, either set of which may be arrested or thrown out of connection at will. I think it preferable, however, to divide the shaft S at its middle and employ two engines of smaller size, because when their cranks are set "quartering" there will be no 80 possibility of stopping on the dead-center. The two parts of the crank-shaft S may be provided with a clutch-coupling, c', whereby, at 85 will, they may be coupled or liberated from each other, as desired.

It is necessary to provide an elastic or flexible coupling between the crank-shaft and pinion-shaft, because there is a constant liability 90 that a variation in level will occur while passing over inequalities in the road—as, for instance, when the wheel rises over a stone the pinion-shaft will thereby be raised above the line of the crank-shaft, and immediately after 95 the pinion-shaft has regained its position the crank-shaft will sink below the line of the pinion-shaft. Such oscillations will always be violent, because sudden, and will soon pull the machine to pieces if not provided against. 100

Slip-joints are not adapted, because the required slip is always vertical and the moment when slip is necessary the joint is liable to be horizontal. "Universal joints," so called, are not adapted, because the same transverse slip 105 must be provided for or the shaft must be made telescopic and two joints inserted. I avoid these difficulties by a link-connection, generically shown in Fig. 10, S being the crank-shaft and d being the pinion shaft, 110 each being provided with an arm, a² a³, respectively, or their equivalents, set at a greater or less angle to each other, not exceeding ninety degrees, and their extremities connected by a link, b'. This link, being flexibly connected at each end to the arms a² a³, respectively, will permit a change of level in either 115 of said shafts without disturbance.

An engine may be competent to maintain motion in a loaded carriage without being able 120 to start the same from a state of rest, and for this reason it is necessary sometimes to provide means for applying the propulsive force gradually. This is well understood in railroad transportation, the coupling of freight-trains being necessarily left loose, so that the cars are set in motion one at a time. Therefore in my road-engines, which are designed to load to the full capacity of the engine, I substitute a volute spring, T, for the link b', 125 one end being attached to a drum, k', on the pinion-shaft d, (said drum being equivalent to

the arm a^2), and the other end is attached to a part, t , on the shaft S , (said part t being equivalent to the arm a^2 .) The part t may advantageously be developed into a fly-wheel, as at U . 5 When the engine is started, the spring T will be gradually wound upon the drum k' , and as gradually will apply the propulsive force to start the machine. Finally, if the power required to propel the machine exceeds the resilience of the spring it will be wound tightly upon the drum, and will draw in a straight line from the surface of the outer coil to the point of attachment with the flange t , and that part of the spring will then act as a drag-rod, 10 but will at all times permit free flexibility between the crank-shaft S and the pinion-shaft d . The axle F of the bearing-wheels E is provided with springs V , as usual, to relieve shock as the machine passes over inequalities 15 in the road.

To protect the gear h and wheel E from obstruction by mud, I place the mud shields or aprons W on each side of the wheel D at the bottom. Said aprons are crescent-shaped 20 plates having the outer or convex edge flanged over or provided with an L-shaped edge flange to enter into the groove exterior to the flange j , where the edge of the apron-flange may fit so closely to the wheel as to practically exclude mud and water. Edge packing may 25 be employed to make such exclusion more complete, if desired. The mud-shields W are suspended from the horizontal arms N' , which will be substantially constant in its position as to the rim-wheel D . Said plates may 30 also be tied together by bolts t' and also squeezed upon the wheel D to the desired degree.

The front end of the machine is supported 35 upon two truck-wheels, $n n$, mounted as usual, with a king-bolt connection with the bolster-frame, so that the truck may rotate to change the direction of said wheels and make them leading-wheels, with which to steer the machine. For the purpose of controlling the 40 leading-truck, the lower part of the fifth-wheel is provided with sprockets, and a sprocket-pinion, p , is mounted on the frame A , with a sprocket-chain, q , whereby the revolution of 45 the sprocket-pinion will revolve and control the fifth-wheel and leading-truck. The pinion p is provided with a shaft and hand-wheel, and may be provided with a ratchet and pawl or other convenient means for locking in position, as it will sometimes be convenient to do; but a worm-wheel, r , and a worm-screw, 50 s , on the hand-wheel shaft is a structure which gives a powerful control and retains the parts in position as left.

55 The lower part of the fifth-wheel is provided with two upwardly-projecting lugs, $u u$, which may, if desired, be provided with friction-rollers, and at each side the frame A is provided with a buffer, v , the purpose being to afford a rest for the frame when the wheels $n n$

are swung far around, as in turning a short corner.

The brakes are applied to the front or truck wheels, because that is thought to be preferable; but they can be applied to the rim D 70 or to the bearing-wheels E , if desired.

The brake-shoes b^2 are attached to swinging frames d' , and in order to balance the pressure I put one set of said shoes in front and another set behind, and operate them both at 75 once by winding the brake-chain around the shaft e' of the brake-wheel f' .

In the drawings I have shown the steering and brake gear located at the extreme front end of the machine; but it will not require invention to change the location of them to the rear end of the machine, where they can be manipulated by the engineer.

It often happens that a road-engine can be profitably employed as a stationary source of 85 power, and to so employ my engine the springs T may be detached from the parts t , and the machine being anchored, the wheels U may be used as band-wheels from which to transmit motion and power to machinery near by. 90

Having described my invention, I claim—

1. In a road-engine, the centerless track-wheel D , provided with an internal cog-rim, h , and a track-flange on each side thereof, combined with the bearing-wheel E , attached 95 to the engine-frame and traveling on said track-flanges, and the box-plate M , attached also to said frame and provided with the arms N , and steady-rollers K at the extremities thereof, and the pinion e , with its shaft d 100 mounted in boxes on said box-plate, as set forth.

2. In a road-engine, the truss-rods $b b'$, and the box-plate M , mounted thereon and provided with bearing-boxes for the pinion-shafts 105 d , and sockets for the steady-arms N , combined with the pinion e , having its shaft in said boxes, the centerless wheel or rim D , provided with a cog-rim, h , in engagement with said pinion and its bearing-wheel E , substantially as set forth, whereby the centerless rim 110 is firmly yet elastically supported.

3. In a road-engine, the centerless rim D , provided with the lateral flanges j , combined 115 with the box-plate M , attached to the frame, the two arms N , each attached at one end to said box-plate and having at the other end sockets $m m$, and the steady-rollers K , in engagement with said flanges, substantially as set forth.

4. In a road-engine, a main frame, a steam-motor and transverse crank-shaft mounted thereon, combined with a centerless track-wheel having an internal cog-rim, a pinion in engagement therewith, and a flexible connection between the shaft of said pinion and said driving-shaft to avoid cramping in passing undulations of the road.

5. In a road-engine, a steam-motor and 125 crank-shaft mounted on the main frame and 130

having at its end a wheel provided with a flange, *t*, combined with a pinion-shaft, *d*, having a drum or hub, *k'*, and a flat spiral spring, *T*, one end fastened to said flange *t* and the other end fastened to said drum *k*, to constitute a flexible connection between said crank-shaft and pinion-shaft.

6. In a road-engine, the centerless track-wheel *D*, having the internal cog-rib, *h*, and

flanges *j*, and the bearing-wheel *E*, combined to with the mud-shields *W* *W*, having the outer edges flanged to enter under the lateral track-flanges *j*, to exclude mud, as set forth.

W. S. WOOTTON.
